(57) **CLAIM**

The ornamental design for a remote control robot, as shown and described.

DESCRIPTION

FIG. 1 is a perspective view of a remote control robot showing my new design;

FIG. 2 is a top view thereof;

FIG. 3 is a left side view thereof;

FIG. 4 is a front view thereof;

FIG. 5 is a right side view thereof;

FIG. 6 is a back view thereof; and,

FIG. 7 is a bottom view thereof.

The broken lines shown in the drawings depict portions of the remote control robot in which the design is embodied that form no part of the claimed design.

1 Claim, 7 Drawing Sheets(56)
